Howard M. Cohn(57) **CLAIM**

The ornamental design for a choking rescue device, as shown and described.

DESCRIPTION

FIG. 1 is a perspective view of a choking rescue device showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof; and,

FIG. 8 is bottom plan view thereof.

The broken lines shown in the drawings illustrate portions of the choking rescue device that form no part of the claimed design.
